UNITED STATES PATENT OFFICE.

GUSTAV A. BUCHHOLZ, OF SHEPHERD'S BUSH, ENGLAND.

IMPROVEMENT IN MANUFACTURE OF SEMOLINA.

Specification forming part of Letters Patent No. 97,036, dated November 23, 1869; patented in England, November 19, 1862.

To all whom it may concern:

Be it known that I, GUSTAV A. BUCHHOLZ, of Shepherd's Bush, county of Middlesex, England, have invented a new and useful Improvement in Machinery for Manufacturing Semolina; and I do hereby declare that the following is a full, clear, and exact description thereof, which will enable others skilled in the art to make and use the same, reference being had to the accompanying drawings, forming part of this specification.

This invention relates to the employment of improved machinery for manufacturing semolina.

In carrying out this manufacture I first hull the wheat intended to be converted into semolina in a novel construction of apparatus, the acting surfaces of which are formed of metal blades, which, when the apparatus is set in motion, give to the grain the friction requisite for removing the outer skin or the greater portion thereof. When the grain has passed through this hulling-machine I separate the bran or hull therefrom in any approved manner, and afterward submit the grain to the action of a novel construction of roller-mill, whereby a large portion will be reduced to semolina fit for market. This I separate by sieves or other suitable means, and the remainder I reduce in any known or approved manner to flour, which may be dressed and finished as usual for the market.

In Sheet I of the accompanying drawings, Figure 1 is a sectional elevation of the improved hulling-machine, showing the construction of the operating parts. Fig. 2, Sheet II, is a horizontal section taken in the line 1 2 of Fig. 1; and Fig. 3 is an irregular vertical section of one of the compartments of the machine detached, the section being taken in the line 3 4 of Fig. 2.

The hulling-machine may be described as consisting of a series of drums, A A, three being the number which I prefer, mounted one above another on the vertical shaft B, and armed at their peripheries with blades *a a*, formed of sheet iron or steel, set radially around the drums A. These drums are inclosed in separate cylindrical chambers C C C, which are concentric therewith, and are set one above the other. The upper ones communicate with the one immediate below them, to allow the

grain passing down from one chamber to the other by means of openings made for that purpose, and regulated by slides or valves.

The peripheries of all the chambers are furnished with gratings of wire-gauze or perforated metal for the discharge through them of bran from those chambers, and they are also fitted with friction-surfaces, composed of blades *c* set in adjustable frames C'.

The shaft B, to which the drums A are keyed, rests in a footstep carried by a bed-plate, D.

Affixed to the bed-plate are standards E E, which serve to carry the chambers C C C. The bottoms of these chambers are severally composed of a circular plate, C', open at the center to allow of the shaft B passing upward through them, and their peripheries are formed of circular castings, with lateral openings to receive the perforated metal for the discharge of the bran and the frames containing the blades *c*.

The plates C' (see the cross-section, Fig. 3) are formed with an annular recess, to receive a series of blades, *c'*, which are arranged radially in the recess immediately below the blades *a* of the drums A. (See Fig. 1.) The plates C' of the upper chambers are also formed with two radial openings, *d*, (see the plan view, Fig. 2,) which openings are capable of being closed by means of slides or valves *d'*, which serve to regulate the discharge of the grain under operation. There are also concentric slots *e e* formed in the plates for allowing the bran to pass down out of the chambers into a chute, *f*, Fig. 1, whence it is conveyed to any suitable receptacle.

The shaft B rotates in a bearing carried by the cruciform casting F, which is bolted to the standards E.

The blades of the drums and cylinders I prefer to form of sheet-steel hardened. They are spaced out by the interposition between every two blades of pasteboard or other filling, of about double the thickness of the blades.

For securing the blades in position I form them with a notch in their working edges, and insert therein a metal band or binder, *g*, which may, if thought desirable, be riveted to the drum-plate or frame, as the case may be.

To provide for the setting up of the blades

as they wear away, the blades *c* are mounted in adjustable frames, which are capable of being slid toward the drums by means of set-screws *h h*.

G is a fan mounted on the shaft *B* and inclosed in a fan-case situate immediately below the lowest chamber *C*. This fan, by its rotation, will draw air through the perforated sides of the mill and between the rubbing surfaces or blades of the drums and chambers, and thereby all tendency of the grain to heat during the process of hulling will be avoided.

The top chamber, *C*, is closed by a cover, which is held down in its place by means of clamping-screws, Fig. 1.

The grain to be operated upon is fed into the top chamber from a hopper, *H*, the feed being regulated by a cup-roller, mounted in the hopper, and driven by a band from the shaft *B*.

Rotary motion is given to the shaft *B* by a band from any first mover passing over a pulley, *B'*, keyed to this shaft.

When the machine is set in motion, the drums will carry round the corn and roll it over and over between the friction-surfaces, thereby disengaging more or less of the skin or hull therefrom.

The amount of friction to which the corn is to be exposed will be determined by the position of the slides *d'*, by which the openings *d* in the plates *C'* may be covered as much as necessary to arrive at the desired result.

When the grains of corn have been detained a sufficient time in the first chamber they will fall into the second chamber and be there similarly acted upon, after which they will escape from this chamber and fall into the third, to be in like manner rubbed by the friction-surfaces therein.

As the bran is disengaged from the corn it will, to a certain extent, pass through the perforated metal before mentioned in the periphery of the chambers, and passing down outside the chambers be discharged into the chute *f*.

The hulled grain will fall through a single opening in the bottom-plate of the lowest chamber into a chute, and be discharged thence out of the machine.

The grain, as it leaves the hulling-machine, will be mixed with a considerable quantity of bran. This I separate by subjecting the grain to the action of a dressing-machine of the ordinary construction.

The hulled grain I now submit to a novel construction of mill (shown at Sheets III and IV) for reducing it to semolina.

Fig. 1 is a cross-section of the mill, the use of which is to rip open the hulled grains submitted to its action. Fig. 2 is a plan view of the same, partly in section.

a a' are a pair of rollers, mounted in bearings carried by a strong frame, *b*. The roller *a* turns in adjustable bearings and the roller *a'* in fixed bearings.

The adjustable roller is kept up to its work

by coiled springs and a transverse bar, *c*, formed with inclined faces, which bear against inclined shoulders of the framing and serve to adjust the pressure of the springs. The bar is moved endwise by the rotation of a transverse screw-shaft, *d*, to which is keyed a disk, *e*. This disk is embraced by a forked piece projecting from the bar. When, therefore, the screw-shaft moves endwise it will draw the bar along with it and cause the compression of the coiled springs. The disk is notched to receive a catch, *f*, that is jointed to the bar *c*, and is intended to insure the bar maintaining its position.

The rollers of the ripping-mill I form with cutting-teeth, produced by making lines of deep cuts on their periphery, which lines cross the axis of the roller, and also cut lines radiating therefrom, as shown in plan at Fig. 3 and in section at Fig. 4. These rollers I gear together, as shown in the drawing, by large and small spur-wheels, by which means I give to one roller a greater surface-speed than to the other.

The hulled grain is delivered to the ripping-rollers by means of the hopper *g*, and in passing between them it is to a great extent reduced to semolina, which may be made fit for the market by being subjected to the operation of winnowing.

The remainder contains a small portion of fine flour and portions of the ripped grain still retaining bran. These several products I separate by means of sieves, and then operate upon the unbranned portions to reduce the same to semolina-flour in any approved manner.

Having now explained the nature of my invention of improved machinery for manufacturing semolina, I wish it to be understood that I claim—

1. A blade for flour-mills fastened in its holder by means of bands *g* and notches or recesses in the working-edge thereof, all as shown and described.

2. The combination of two ripping-rolls, *a a'*, having teeth formed by the intersection of oblique deep-cut lines on their peripheries, with the feeding mechanism shown and described.

3. The combination of two or more pairs of rubbing-surfaces, *a a'*, arranged one above another, with circular plates *C*, having radial openings *d* to pass the grain from one pair to another, in the manner set forth.

4. The combination of transverse bar *c*, having inclined faces, frame having shouldered inclines *b*, screw-shaft *d*, disk *e*, and catch *f*, all arranged as and for the purpose specified.

The above specification signed by me this 12th day of July, 1869.

G. A. BUCHHOLZ.
